WATCH MOVEMENT FOR FANCY WATCHES

Henri Colomb, Tavannes, Switzerland

Application August 5, 1932, Serial No. 627,639
In Switzerland September 4, 1931

10 Claims. (Cl. 58—59)

The present invention relates to a watch movement for fancy watches especially for wrist watches where the barrel meshes directly with the center wheel pinion.

5 According to the present invention the center wheel axis is out of center and is placed with the barrel within one of the two divisions separated by a transverse center line of the movement. The axis of the hands is located on said 10 center line and a toothed cannon frictionally fitted upon said center wheel pinion is provided for working the hands by means of at least one cannon pinion carrying the minute-hand.

This arrangement has particular advantages. 15 Applied to an elongated wrist watch it permits the location within the available space of a barrel, a train of gears, an escapement and a relatively large balance, all these for enlarging appreciably the available space, ordinarily very 20 limited, for the winding and the hand-setting gears.

In a fancy watch having the seconds axis on the longitudinal center line the arrangement according to the present invention will be very 25 advantageous and in the self-winding watches this arrangement allows placing the barrel at one of the ends of the movement and the driving train and the escapement at the other end of the design to save the space for putting in a 30 powerful winding gear.

The annexed drawings show several working forms according to the present invention.

Fig. 1 is a diagrammatical plan view of an 35 elongated movement $3\frac{3}{4}''$,—9 x 21 millimeters—according to the invention.

Fig. 2 is a section on line II—II in Fig. 1.

Fig. 3 is a similar plan like that of Fig. 1 but for another working form.

Fig. 4 is a section on line IV—IV in Fig. 2, 40 Fig. 5 a section on line V—V in Fig. 1 and Fig. 6 a section on line VI—VI in Fig. 2.

Fig. 7 is a diagrammatical plan of a movement having the axle of the seconds on the longitudinal axis of the movement and having a cylindrical 45 escapement.

Fig. 8 shows in plan and as far as is needed for clearness a movement according to the present invention and of the form called "tonneau".

50 Fig. 9 and Fig. 10 are diagrammatical plan views referring to the hand-setting gears and the minute work.

Fig. 11 is a diagrammatical view of a detail which shall be explained further on.

55 Fig. 12 is a plan view of a self-winding watch

having the arrangement according to the invention.

Fig. 13 is a similar view of a watch having the second-hand axis on the longitudinal axis of the movement, the showing of the swinging weight 5 being omitted.

Fig. 14 is a section on the line 14—14—14 of the preceding figure and

Fig. 15 is a section on the pivot axis of the swinging mass of the forms according to Fig. 12 10 or 13.

Referring to the Figs. 1 and 2, the barrel A meshes with the center wheel pinion a to the axle of which is also fixed the center wheel B. This axle is generally located at the center of a watch 15 movement or in a fancy watch it is situated at the intersection of the transverse or minor and the longitudinal or major axes. In the present invention this pinion is entirely displaced from the center. It is located on the left hand side 20 of the plate I, if this plate is considered to be divided into two halves by the axis x—x.

Two particular features of this construction permit the disposition on said plate of a barrel, 25 a driving gear, an escapement and a balance relatively large so as to enlarge the space left for the winding and the hand-setting gears. The first feature consists in putting the center wheel out of the watch's center in a longitudinal sense in order to put the barrel at the end of the 30 plate and the second feature is the transverse displacement which makes it possible to solve the problem. Besides in spite of a larger center wheel the longitudinal displacing of it makes it 35 possible to avoid the inconvenience of almost all such fancy watches, namely, that the support of the contrate wheel is rendered unsafe by the passage of the center wheel.

In a fancy watch of the type called "baguette" 40 where the length as compared to the width is ordinarily greater than in the described example the eccentric position of the center wheel pinion which places the barrel at the extremity of the plate would be still more apparent, for in the 45 said fancy watch having the pinion at the center of the movement 2 to 4 millimeters of the length of the plate next to the barrel remain non-utilized. According to the invention this place can be utilized for placing into the same watch a driving train, an escapement and a larger 50 balance. In certain cases it will be possible to dispose the lever escapement on one side on account of the small space available for a normal escapement on a straight line.

The manufacturing of such watches for the 55

reasons given will be facilitated, the quality will be improved and the manufacturing cost diminished.

The center wheel is as a rule connected with the balance G by the intermediate wheels b, C, c, D, d, E and the lever F. Only the two pallet stones are shown in Fig. 1.

Upon the center wheel pinion a is mounted with frictional contact a wheel H which meshes 10 with wheel O which, in turn, meshes with the cannon pinion J which is fixed to the stud K. The cannon pinion J moves the minute wheel I the pinion M of which moves the wheel N. L designates the wheel for time setting. The longitudinal section shown in Fig. 2 shows that there 15 is no particular difficulty to dispose the driving gear and the escapement nor to obtain a flat movement. All parts in Fig. 2 are marked with the same letters of reference as corresponding 20 parts in Fig. 1.

In the fancy watch 9 x 21 millimeters of Figs. 1 and 3 it is possible according to the invention to use for the third wheel, seconds wheel and escapement wheel two pinions of seven and one of 25 six teeth, while ordinarily only three pinions of six teeth are possible.

It must be noted that in this working form the 30 parts of the movement which make the quality and fix the price, to wit: the barrel, the escapement and the balance, have exactly the dimensions which will permit them to be mounted in a plate 10 x 23.7 millimeters of the conventional type of movement when the center wheel is disposed at the center of the movement. But here 35 the plate is sensibly smaller, namely, 9 x 21 millimeters.

In the working form of the Figs. 3 and 4 where 40 similar parts are marked with the same letters of reference as in Figs. 1 and 2 the wheel O is omitted. The minute wheel I substitutes said wheel and transmits the movement of the wheel H which is concentric with the center wheel pinion to the cannon pinion J. Due to this construction the axes of the pinion b and the seconds pinion c are close to the minute wheel I.

The Fig. 7 represents a watch movement of the 50 type called "baguette" with a cylindrical escapement. The arrangement of the barrel and of the center wheel pinion allows the use of a larger driving train than is usual. Here also the minute wheel forms the intermediate member between pinion H and the cannon pinion J or the cannon pinion M. Here the arrangement of the driving train according to the present invention 55 makes it possible to dispose the axis of the second-hand pinion on the longitudinal axis y-y of the plate. This result cannot be obtained with the generally used arrangement of parts.

The Fig. 8 represents the arrangement according 60 to the present invention applied to a fancy watch of the type "tonneau" where all the wheels are represented. Besides the whole series of parts already enumerated with regard to Figs. 1 to 7, an additional pinion u and an additional wheel 65 V have been intercalated here. These additional members transmit the movement from the center wheel B to the pinion b of the third wheel. In this case the wheel H meshes directly with the cannon pinion J which is of course at the center.

In the shown arrangement the center wheel 70 pinion is likewise out of center and located within one of the two halves of the plate separated by the transverse center line on which is also located the axis of the watch hands. Directly due to this 75 it is possible to dispose not only a large barrel

of 11 lines, but also a proportionately large balance. In a watch of 8 3/4 lines of the design "tonneau" measuring 19.7 x 26.5 millimeters over all the contrivance of placing the center pinion out of center makes it possible to put in a balance 5 of 950/100 millimeters diameter which corresponds to a normal watch of 10 1/2 lines. The presence of the additional wheel between the center wheel and the third wheel facilitates 10 greatly the distributing of parts. It is possible to keep all the wheels except the center wheel at a sufficient distance from the balance and the third wheel from the lever, so that these wheels do not interfere with the movements of the balance. The pallets of the lever are well cleared 15 and the mounting of the escapement is rendered easier.

Figs. 9 and 10 show a watch movement of the 20 design "tonneau" from the side of the dial and two ways of connection of the hand-setting gears with the sleeve of the crown gear S.

In the Fig. 9 it is the wheel L which moves, by 25 means of the minute wheel I, the cannon pinion J while in the Fig. 10 this cannon pinion is moved by means of the intermediate wheels L, O and H. T designates the drum of the barrel. The other wheels have the same letters of reference as in the former examples.

In the Fig. 11 it is the wheel L of the hand-setting mechanism which is intermediate between the cannon pinion J and the wheel H which is frictionally fitted on the center wheel shaft. The minute wheel I meshes then only with the cannon pinion.

The Fig. 12 relates to a self-winding watch 35 where the arrangement of the barrel and of the center wheel pinion according to the present invention has been accepted. The figure gives a grammatical view of the gearing and the escapement with its balance. All the wheels are designated by the same letters of reference as in the preceding examples. The bridges of the movement have been left out and the hand-setting mechanism whereof the stem is located in the transverse center line Z-Z of the watch is only indicated by a rectangle 13 representing the window 40 for the sleeve with clutch and conrate teeth.

The winding weight 14 is very powerful. It 50 fills the whole thickness of the watch case in the largest part of the left hand division of the Fig. 12. This considerable advantage is a direct result of using an arrangement according to the present invention by having the center wheel pinion put out of the center of the watch and a toothed wheel mounted with frictional contact 55 for setting the hands.

The rectangular watch case with slanted or 60 cut-off corners of this example measuring 21 x 31 millimeters possesses a barrel, a driving train, an escapement and a balance of 10 1/2 lines; and all 65 the wheels of the movement from the barrel to the escape wheel included and the axis of the balance are disposed on the one side of the plate the minor axis of the watch forming the limit. It is owing to the invention that this combination has been possible and that such a space could have been saved for the winding weight 14.

The Fig. 15 will help to explain the following 70 statements. The winding weight 14 is rotatably guided on the pivot pin 15 by means of two bushes e² fixed to the ends of a cannon e¹ integral with said weight. This pivot pin is forced with one end into the plate and supported at the other end by a cock 16 which limits at the same time all axial play of the weight. The oscillations 75

the weight are transmitted to the ratchet wheel 21 by means of a pawl 21' and thence to pinion 22 integral with the ratchet wheel 21 and from here to a wheel 23 fast to the pinion 24 which controls 5 the ratchet 25 and the spring of the barrel.

The stop pawl, 26 pivoted at 27, is held engaged with teeth of the ratchet 21 by a spring 28 attached to a stud 29. The operation of this working example is easily understood from the described construction. 10

In the working example according to the Figs. 13 and 14 the arrangement of the self-winding movement of the driving train and of the escapement are the same as in the example just described. But here the center wheel B meshes 15 with a pinion 32 riveted to a wheel 33 which is pivoted on a staff 35 fixed to a cock 36. The wheel 33 meshes with a seconds wheel pinion 34 at the center of the watch. This pinion is pressed 20 upon the staff 38 which carries the second-hand 39. A brake spring 40 is fixed to a stud 41 which is held by frictional contact in the barrel bridge 3 and adapted to regulate the friction of the spring 40 which bears upon a cannon provided 25 on the staff 38 right above the pinion 34.

The cannon K upon which the cannon pinion J is revolvably mounted is pressed into the plate 1 and carries near each end a bearing for the staff 38. In this way the indications of the second-hand are exact for the resulting friction takes 30 off the damaging effect of the play between the gears connected with this second-hand.

What I claim is:

1. In a watch of the character described, an 35 oblong plate, concentric minute and hour-hand-carrying spindles mounted at the intersection of the major and minor axes of said oblong plate, a toothed driving barrel positioned on said plate entirely on one side of the minor axis thereof, a 40 center wheel, a shaft carrying said center wheel and laterally spaced from the hands-carrying spindles, a center wheel pinion affixed to said shaft and meshing with teeth on said barrel, said center wheel pinion and the shaft carrying 45 the same being mounted entirely on the same side of the minor axis of the oblong plate as the barrel, and a pinion frictionally mounted on said shaft for driving said hands-carrying spindles.

2. In a watch of the character described, an 50 oblong plate, concentric minute and hour-hand-carrying spindles mounted at the intersection of the major and minor axes of said oblong plate, a toothed driving barrel positioned on said plate entirely on one side of said minor axis, a center 55 wheel, a shaft carrying said center wheel and laterally spaced from the hands-carrying spindles, a center wheel pinion affixed to said shaft and meshing with teeth on said barrel, said center wheel pinion and the shaft carrying the same 60 being mounted entirely on the same side of the minor axis of the oblong plate as the barrel, hands-carrying and moving mechanism, a pinion frictionally mounted on said shaft for driving said mechanism, a balance wheel unit positioned 65 entirely on the opposite side of said minor axis, and a gear train for transmitting motion from said center wheel to said balance mechanism.

3. In a watch of the character described, an 70 oblong plate, a toothed driving barrel positioned on said plate entirely on one side of the minor axis thereof, a center wheel, a shaft carrying said center wheel, a center wheel pinion affixed to said shaft and meshing with teeth on said barrel, said center wheel pinion and the shaft carrying 75 the same being mounted entirely on the same side of the minor axis of the oblong plate as the barrel. 75

the same side of the minor axis of the oblong plate as the barrel, concentric hollow spindles mounted at the intersection of the major and minor axes of said plate and carrying minute and hour-hands, a pinion affixed to the spindle 5 carrying the minute-hand, a pinion frictionally mounted on the center wheel shaft, and intermediate gear means for transmitting motion from said frictionally mounted pinion to the pinion on said minute-hand spindle. 10

4. In a watch of the character described, an oblong plate, a toothed driving barrel positioned on said plate entirely on one side of the minor axis thereof, a center wheel, a shaft carrying said center wheel, a center wheel pinion affixed to said 15 shaft and meshing with teeth on said barrel, said center wheel pinion and the shaft carrying the same being mounted entirely on the same side of the minor axis of the oblong plate as the barrel, concentric hollow spindles mounted at the intersection of the major and minor axes of said plate and carrying minute and hour-hands, a pinion affixed to the spindle carrying the minute-hand, a pinion frictionally mounted on the center wheel shaft, intermediate gear means for transmitting 20 motion from said frictionally mounted pinion to the pinion on said minute-hand spindle, a balance mechanism positioned entirely on the opposite side of said minor axis, and a gear train for transmitting motion from said center wheel to said 25 balance mechanism. 30

5. In a watch of the character described, an oblong plate, concentric hands-carrying spindles mounted at the intersection of the major and minor axes of said plate, a spring actuated driving barrel, a balance, intermediate gears and pinions, all having their axes mounted on one side of the minor axis of said plate, and a weighted winding mechanism having the actuating weight positioned on the opposite side of said minor axis 40 of the plate. 35

6. In a watch of the character described, an oblong plate, an hour-hand spindle, a hollow minute-hand spindle concentric with the hour-hand spindle, a spring actuated driving barrel having 45 teeth on the periphery thereof, a center wheel, a center wheel pinion meshing with said barrel, a shaft carrying said center wheel and pinion, said center wheel pinion and the axis of said barrel being mounted entirely on one side of the 50 minor axis of said plate, a pinion frictionally mounted on said shaft, gear wheels for transmitting motion from said frictionally mounted pinion to said hollow minute-hand spindle, an escapement mechanism, gear wheels connecting the escapement mechanism with said center wheel, the axes of all of said wheels and of said escapement mechanism being positioned on the same side of said minor axis as said barrel, and a weighted winding mechanism having the actuating weight positioned on said plate on the opposite side of said minor axis. 55 60

7. In a watch of the character described, an oblong plate, concentric minute and hour-hand-carrying spindles mounted at the intersection of the major and minor axes of said oblong plate, a toothed driving barrel positioned on said plate entirely on one side of the minor axis thereof, a center wheel, a shaft carrying said center wheel and laterally spaced from the hands-carrying 70 spindles, and a center wheel pinion affixed to said shaft and meshing with teeth on said barrel, said center wheel pinion and the shaft carrying the same being mounted entirely on the same side of the minor axis of the oblong plate as the barrel. 75

8. In a watch movement for wrist watches, an oblong plate, concentric hands-carrying spindles, a toothed driving barrel, a pinion meshing with said barrel, a shaft transversely spaced from said hands-carrying spindles and carrying said pinion, and a second pinion on said shaft for transmitting driving movement to said hands-carrying spindles, the barrel and pinions being positioned on one side of an axis extending transversely 10 across said plate and passing through the axis of the hands-carrying spindles.

9. In a watch movement for wrist watches, an oblong plate, concentric hands-carrying spindles, a toothed driving barrel, a pinion meshing 15 with said barrel, a shaft transversely spaced from said hands-carrying spindles and carrying said pinion, a second pinion on said shaft for transmitting driving movement to said hands-carrying spindles, the barrel and pinions being positioned 20 on one side of an axis extending transversely

across said plate and passing through the axis of the hands-carrying spindles, a center wheel on said shaft, a seconds pinion, a shaft carrying the seconds pinion, a third wheel meshing with said seconds pinion, and a pinion carried by said 5 third wheel and meshing with said center wheel, the third wheel and the shaft carrying the seconds pinion being mounted on the plate on the same side of said transverse axis thereof as the barrel.

10. In a watch movement for wrist watches, an oblong plate, concentric hands-carrying spindles, and a spring driven watch movement including a plurality of gear wheels and pinions and an escapement and balance unit, the axes of all of 15 which lie on one side of an axis extending transversely across said plate and passing through the axis of the hands-carrying spindles.

HENRI COLOMB. 20
